Primary Examiner — Rhea Shields**CLAIM**

The ornamental design for a clamshell packaging container, as shown and described.

DESCRIPTION

FIG. 1 is a perspective view of a clamshell packaging container in an open configuration;

FIG. 2 is a rear view of the clamshell packaging container of FIG. 1 in an open configuration;

FIG. 3 is a front view of the clamshell packaging container of FIG. 1 in an open configuration;

FIG. 4 is a right view of the clamshell packaging container of FIG. 1 in an open configuration;

FIG. 5 is a left view of the clamshell packaging container of FIG. 1 in an open configuration;

FIG. 6 is a top view of the clamshell packaging container of FIG. 1 in an open configuration; and,

FIG. 7 is a bottom view of the clamshell packaging container of FIG. 1 in an open configuration.

In the drawings, the broken lines are for the purpose of illustrating portions of the clamshell packaging container that form no part of the claimed design.

1 Claim, 5 Drawing Sheets(56)
